UNITED STATES PATENT OFFICE.

RUSH ELKINS, OF GILBERT, WEST VIRGINIA.

LAMP BURNER.

Application filed February 1, 1922. Serial No. 533,276.

To all whom it may concern:

Be it known that I, RUSH ELKINS, a citizen of the United States, residing at Gilbert, in the county of Mingo and State of 5 West Virginia, have invented certain new and useful Improvements in Lamp Burners, of which the following is a specification.

This invention relates to lamps and more particularly to a burner.

- 10 The primary object of this invention resides in the provision of a lamp burner which consists of an embodiment of elements that prevent the accidental displacement of the chimney from the oil reservoir. 15 A further object of this invention resides in the provision of a lamp burner which consists of an embodiment of elements that retain the lamp chimney in a secure position on the oil reservoir and securely dis- 20 poses the wick guide in the proper position.

With these and other objects in view, this invention resides in certain novel features of construction and combination of elements which will be more fully set forth in the 25 specification herewith and pointed out in the appended claim, it being understood that the right is reserved to resort such departures from the present disclosure as come within the scope of the claim.

30 In the accompanying drawing:—

Figure 1 is a side view of a portion of lamp showing a chimney supported thereon, by the burner which comprises this invention.

35 Figure 2 is an enlarged sectional view through the burner.

In the present embodiment of this invention the letter L designates the oil reservoir of a lamp which has an upstanding flange 1 40 that is provided with screw threads.

Removably engaged with said flange 1 is the screw threaded end 8 of a collar 5 adjacent the central portion of which it is provided with an annular bead 9 which forms an annular channel for the reception of the 45 base 10 of the wick guide 16. The aforesaid bead supports the wick guide 16 and has a notched lug 14 pressed therefrom which is adapted to project within an annular groove 18 in the stem 20 of the wick 50 lift to prevent its displacement when in operative position.

The upper portion of the collar 5 is provided with screw threads 6 for the reception of the screw threaded end c of the 55 chimney C, thus rendering it impossible to displace the chimney by transporting the lamp from place to place.

In the production of a lamp of the above character it is manifest that the expense 60 of manufacture is reduced to a minimum with the assurance that the cost of replacing the several parts and especially the chimney will be nearly eliminated.

Having thus described my invention what 65 I claim is:

In an article of the character described, the combination with an oil reservoir, a collar supported thereon, a wick guide supported by said collar, a wick lift having an 70 annular groove in its stem, a lug on said wick guide and projecting in the annular groove of the stem of said wick lift, and a screw threaded chimney engaging said collar.

75 In testimony whereof, I affix my signature.

RUSH ELKINS.
